United States Patent

Des. 241,693
Patented Oct. 5, 1976

241,693

SEAT

Ira S. Friedman, Somerset, N.J., assignor to
Rowe Furniture Corporation

Filed July 3, 1975, Ser. No. 593,061

Term of patent 14 years

Int. Cl. D6—01

U.S. Cl. D6—63

FIG. 1

FIG. 2

FIG. 3

FIG. 4

FIG. 1 is a front perspective view of a seat showing my design in the form of a davenport;

FIG. 2 is a side elevation of the wood trimmed furniture seat illustrated in FIG. 1;

FIG. 3 is a rear elevation of the wood trimmed furniture seat illustrated in FIG. 1; and

FIG. 4 is a front perspective view of the wood trimmed furniture seat illustrated in FIG. 1, shown in the form of a love seat.

The sides of the davenport and love seat not shown are identical to those which are shown.

I claim:

The ornamental design for a seat, substantially as shown and described.
